(57) **CLAIM**

The ornamental design for a golf clubhead, as shown and described.

DESCRIPTION

FIG. 1 is a front elevational view of the golf clubhead;

FIG. 2 is a left side perspective view thereof;

FIG. 3 is a rear elevational view thereof;

FIG. 4 is a bottom perspective view thereof;

FIG. 5 is a bottom plan view thereof;

FIG. 6 is a top plan view thereof;

FIG. 7 is a front elevational view of a second embodiment of the golf clubhead as disclosed in FIG. 1;

FIG. 8 is a front elevational view of a third embodiment of the golf clubhead as disclosed in FIG. 1; and,

FIG. 9 is a front elevational view of a fourth embodiment of the golf clubhead as disclosed in FIG. 1.

The undisclosed sides of the second, third and fourth embodiments are identical to those disclosed in the first embodiment.
